UNITED STATES PATENT OFFICE.

JULIUS C. RUEDT, OF MILWAUKEE, WISCONSIN, ASSIGNOR TO PHOENIX HOSIERY COMPANY, OF MILWAUKEE, WISCONSIN, A CORPORATION OF WISCONSIN.

GARMENT.

Application filed August 7, 1922. Serial No. 580,011.

To all whom it may concern:

Be it known that I, JULIUS C. RUEDT, a citizen of the United States, residing at 764 42nd Street, Milwaukee, in the county of Milwaukee and State of Wisconsin, have invented a certain new and useful Improvement in Garments, of which the following is a full, clear, concise, and exact description, reference being had to the accompanying drawings, forming a part of this specification.

My invention relates to clothing, and more specifically to any garment held in place by bands or straps passing over the shoulders of the wearer.

One object of the invention is to provide simple and improved means for adjusting the length of such shoulder straps.

Another object is to eliminate the use of metallic clips or buckles for this purpose. By such elimination I avoid one of the most serious objections to the use of adjustable shoulder straps on garments worn next the person of the wearer.

Another object is to extend the use of adjustable shoulder straps to garments ordinarily worn next the person of the wearer.

Another object is to make it possible to adjust the exact height at which the garment is held without changing its shape.

Another object is to make this adjustment continuous over a wide range.

Another object is to provide for making the adjustment quickly and easily by the wearer with the shoulders of the wearer in normal position.

It will be apparent that my invention is applicable to garments generally, including workmen's garments of the over-all type, garments used in bathing, and ladies' undergarments, which last are at present universally provided with shoulder straps which are not adjustable.

Further objects and advantages of the invention will become apparent as the description proceeds.

In the accompanying drawings:

Figure 1 is a front view of a portion of a garment according to my invention in position on the wearer; and

Figure 2 is a rear view of the same.

In the embodiment of my invention selected for illustration, the shoulder strap 10 is formed of a single piece of material attached at one end, as at 12, to the upper edge of the

front portion of the garment. It passes over the shoulder and down in the rear as at 14 into a tubular hem 16 lying along the upper edge of the garment and extending from the point where the strap enters it under the arm and across the front to substantially the middle at 18. The strap passes through the tubular hem and projects beyond the same at 20. The projecting ends of the straps may be tied together, and by 60 sliding the straps in the tubular hem and tying them, the length of the portion passing over the shoulder may be suitably adjusted.

In case the garment is of light material or 70 easily stretched, or in case the strains imposed thereon by movement of the wearer make it desirable, the garment may be reinforced in the back between the ends of the hems 16 by another hem or reinforcing strip 75 22 to take the tension tending to pull the ends of hems 16 apart, and properly support the back of the garment.

Without further elaboration, the foregoing will so fully explain the gist of my invention, that others may, by applying current knowledge, readily adapt the same for use under various conditions of service. It will, for instance, be obvious that hems 16 and 22 may be formed of the same fabric as 80 the body of the garment, and of the same piece of fabric as that constituting the body of the garment, whether the garment is knitted, made of woven fabric, leather, fine mesh wire cloth, or any other material. It will 85 be equally obvious that they may, and often will be, as in the embodiment disclosed, formed of separate pieces of material of different texture and strength from the body of the garment. The end attachments at 12 90 in the embodiment disclosed, are spaced from the middle of the garment, about halfway to the side, but it will be obvious that these points could both be attached in the middle. By varying the points of attachment of ends 12, a large number of attractive designs of garments can be produced.

It will be apparent that hems 16 might extend from the middle only part way to the side and the straps pass from the back over the shoulder to the front and to the center to be tied.

As applied to ladies' undergarments, embodiments of my invention may be made particularly convenient and attractive when 110

2
no part of the garment except the tension member passes over the shoulder, as distinguished from those in which the garment itself, or lace attached thereto, passes over the shoulder, and a drawstring round the neck is provided.

Many modifications and alterations may be made by those skilled in the art without eliminating certain features which may 10 properly be said to constitute the essential items of novelty, which items are intended to be defined and secured to me by the following claims:

I claim:—

- 15 1. In a garment, a body portion, means for slidably guiding a strap member at the upper edge and on each side of said body portion, and strap members fixedly attached to the upper edge of said body portion and 20 extending through said guiding means and adapted to be tied together between said guiding means.
2. In a garment, a body portion adapted to encircle the body of the wearer under the

arms, means for slidably guiding a strap 25 member at the upper edge, under the arms, at the front and on each side of said body portion, and strap members extending from a point of attachment to the upper edge of said body portion at the front, adapted to 30 pass over the shoulders of the wearer, and entering the respective guiding means at the back and passing forwardly therethrough under the arms to the front where they meet each other to be tied together. 35

3. In a garment, a body portion having an open ended hem extending along the upper edge thereof on each side from back of the arms of the wearer forwardly under them and across the front to the center, and 40 straps, each attached to a side of the front upper edge of said body portion, said straps being adapted to pass over the shoulders of the wearer and then forwardly through the 45 hems.

In witness whereof, I hereunto subscribe my name this 3rd day of August, 1922.

JULIUS C. RUEDT.
